WATER SUPPLY FOR FIRE PUMPS OR ENGINES.

No. 518,776.

Patented Apr. 24, 1894.

UNITED STATES PATENT OFFICE.

HENRY C. CAMPBELL, ISABELLA CAMPBELL, AND MINNIE A. MILLARD, EXECUTORS OF GARDINER CAMPBELL, DECEASED, AND GEORGE G. CAMPBELL, OF MILWAUKEE, WISCONSIN; SAID EXECUTORS OF SAID GARDINER CAMPBELL ASSIGNORS TO GEORGE G. CAMPBELL AND HENRY E. CAMPBELL, OF SAME PLACE.

WATER-SUPPLY SYSTEM FOR FIRE PUMPS OR ENGINES.

SPECIFICATION forming part of Letters Patent No. 518,776, dated April 24, 1894.

Application filed January 23, 1893. Serial No. 459,500. (No model.)

To all whom it may concern:

Be it known that GARDINER CAMPBELL, deceased, and GEORGE G. CAMPBELL, both of the city of Milwaukee, in the county of Milwaukee and State of Wisconsin, did jointly invent new and useful Improvements in Water-Supply Systems for Fire Pumps or Engines; and we HENRY C. CAMPBELL, executor, and ISABELLA CAMPBELL and MINNIE A. MILLARD, *née* CAMPBELL, executrices of the said GARDINER CAMPBELL, deceased, and the said GEORGE G. CAMPBELL, do hereby declare the following to be a full, clear, and exact description of said invention, reference being had to the accompanying drawings, and to the letters of reference marked thereon, which form a part of this specification.

Our invention relates to improvements in water supply systems for fire pumps or engines.

The object of our invention is to provide a more copious supply of water from the hydraulic mains of a city than can be obtained from the ordinary hydrant, and also, whereby the number of engines supplied at a given place, is not limited to the number of hose connections of the hydrant.

The construction of our invention is explained by reference to the accompanying drawings, in which—

Figure 1, represents a vertical section of the water reservoir. Fig. 2, is a cross section of a cap or shield and a discharge duct drawn on line 2—2 of Fig. 1. Fig. 3, is a plan, showing parts in section drawn on line 1—1 of Fig. 1. Fig. 4 represents a top view of the device for simultaneously operating the inlet and outlet valves of the water reservoir, drawn on line 4—4 of Fig. 5. Fig. 5 is a side view of the device shown in Fig. 4, drawn on line 5—5 of said figure. Fig. 6, represents a cross section of an adjustable discharge duct, drawn on line 6—6 of Fig. 1. Fig. 7, represents a bottom view of the cover of the reservoir.

Like parts are represented by the same reference letters throughout the several views. A' is a metallic reservoir which is prefer-

ably made of cast iron in a series of sections B—B—B, the upper edge of each section being enlarged to receive the lower edge of the next succeeding section above it. The upper section C converges slightly forming a short neck which is provided with an annular flange D for the reception of the cover E. It is obvious that by thus forming the reservoir of separate sections as shown, the height of the reservoir may, by adding or removing a section, be varied to conform to the level of the street or to any change made in grade of the street after the reservoir is set, it being intended to locate the mouth of the reservoir at or near the level of the street, while the bottom of the reservoir is located at or near the level of the water main.

F is the bottom of the reservoir, which is provided with a vertical, annular flange G, which incloses the lower edge of the lower section B.

Water is conducted to the reservoir A from the hydraulic mains through the S shaped pipe or duct H. The duct H is formed in the peculiar angular shape shown to facilitate connecting the reservoir with water mains located on different planes. When the water main is above the inlet aperture of the reservoir the pipe H is turned upward in the position shown. When the water main is below, the free end of the pipe H is turned downward and when the water main is located at any intermediate level between the two extremes, the free end of such pipe is turned toward the right or left until it is brought in line with the water main, whereby said pipe has a range of adjustment of several feet upward or downward, which greatly facilitates connecting the reservoir with the water mains as stated.

J, is an ordinary gate valve, by which the admission of water from the water mains is controlled and regulated.

K, is a valve rod which communicates from the valve to near the upper end of the reservoir, at which point it is provided with a removable handle L, by which the rod is turned

toward the right and left and the valve thereby opened or closed.

To prevent turning the valve rod in the wrong direction as might otherwise be attempted in the haste and excitement of opening it in case of fire, the upper end of the rod K is provided with a ratchet wheel M' against the teeth of which the pawl N engages in such a manner as to prevent said rod from being turned downward. When, however, it is desired to close the gate valve the pawl N, is thrown back out of contact with said teeth.

When the reservoir A is not being used it is desirous to permit the water to escape therefrom. To accomplish this object, the valve O is provided, through which valve when open, the water flows into the horizontal duct P, to the sewer. The duct P, is preferably cast contiguous with the bottom F. The valve O is held open when the reservoir is not in use by the chain Q, which chain is suspended through the handle R within the recess S, which recess is formed in the edge of the bracket T. The lower end of the handle R is provided with a collar, U, which engages on the upper side of the pawl N, whereby said valve O is prevented from closing of its own gravity.

Lest it might be forgotten to close the outlet valve O before opening the inlet valve, the handle R is made to depend for its support in said recess upon said pawl N. It follows that as soon as the valve rod of the inlet valve is turned in the act of opening said valve, said pawl is thrown back from said suspended handle R by contact with the teeth of the ratchet wheel L, whereby said handle is released and said valve O is permitted to close.

A' is a cap or shield located above, in front, and partially around the discharge duct of the valve J, and is so constructed as to stop the force and agitation of the water as it rushes in from the water mains, and prevents the whirling movement which would interfere with the proper working of the fire pumps. The cap A' is rigidly bolted at one end to the discharge duct of the valve J and rests at the other end upon the bottom of the reservoir.

To prevent the reservoir from over-flowing by the excess of the supply of water over the capacity of the fire pumps, a discharge pipe B' is provided, the mouth of which is located or adjusted at the desired level of the water in said reservoir, whereby, when the water reaches such level the excess will over-flow into said discharge pipe, from whence it escapes out, through the duct P, to the sewer.

As an additional means for maintaining the water at the desired level in the reservoir, a secondary valve C' is provided at the discharge end of the valve J, which valve C' is fitted loosely in its bearings so as to be easily moved by the automatic action of a float and counterbalance; it not being intended to entirely stop the inlet of water thereby but only

to diminish the flow to correspond with the quantity drawn from the reservoir, the valve C' is suspended from the lever D'. The lever D' is centrally supported by the standard F' upon the pivot G'. The free end of the lever D' is provided with an adjustable weight H', which counterbalances the valve C' and causes it to remain in the open position. The float I is connected with the free end of the lever D' by a chain J', whereby as the water in the reservoir rises above the level of the discharge pipe B' the float will be buoyed up, when acting through the chain J', and lever D' will close the valve C'. Thus, it is obvious that the valve C' will be caused to open and close to conform to the change of level of the surface of the water and a nearly uniform level of water be thereby maintained in the reservoir. To provide for protecting the valve and inlet ducts from injury by frost the valve J is partially opened to admit a small stream of water when the valve K is opened whereby when the water has covered the inlet valves and ducts and reaches the level of the valve K' it escapes from the reservoir through the pipe B'. The valve K' is provided with a chain L' by which it may be opened and closed from the mouth of the reservoir.

The vertical pipe or duct B' is preferably formed in two sections a and b, one of less diameter than the other, which are telescoped together so as to adjust its inlet end to any desired level. When the section b is adjusted it is secured at such point by set-screws d-d as shown in Fig. 6.

It is obvious that by forming the reservoir A in sections as shown, the pipe connecting section or section b by which the inlet pipe is connected with said water mains, may be located either at the bottom of the reservoir at any intermediate point between the bottom F and the converging top C, to correspond with the level of the said water mains, without changing the relative position of either the top or bottom of the reservoir to each other or to the surface of the ground.

Having thus described the invention, what is claimed as new, and desired to be secured by Letters Patent, is—

1. In a water supply system for fire pumps or engines the combination of a water reservoir A, inlet hand actuated water controlling valve J, vertical valve rod K, communicating from said hand valve J to the mouth of said reservoir, outlet duct B' communicating from near the top of said reservoir with the exterior and drain-pipe P provided with valve O and operating chain Q, substantially as and for the purpose set forth.

2. In a water supply system for fire pumps or engines the combination of the water reservoir A, inlet water controlling valve J, outlet duct or pipe B', S-shaped inlet duct H, drain pipe P provided with valve O, and operating chain Q, substantially as and for the purpose specified.

3. In a water supply system for fire pumps

or engines the combination with a water reservoir provided with inlet duct and water controlling valve and an outlet duct for the escape of surplus water of a cap or shield A', and a secondary float actuated valve located between said water controlling valve and said cap or shield, substantially as and for the purpose specified.

4. In a water supply system for fire engines or pumps the combination with a water reservoir provided with inlet duct and water controlling valve and an outlet duct for the escape of surplus water, of a secondary float actuated valve C' centrally pivoted valve supporting lever D' counter-weight H' operating chain J' communicating from said pivoted lever D' to an actuating float I' all substantially as and for the purposes specified.

5. In a water supply system for fire pumps or engines the combination of the water reservoir A provided with inlet and outlet ducts, water controlling valves and an over-flow discharge pipe or duct of the drain duct P communicating from the bottom of the reservoir with the exterior, valve O and valve operating chain Q connecting from said valve to the mouth of said reservoir, substantially as set forth.

6. In a water supply system for fire pumps or engines the combination of the valve rod K, ratchet wheel M, pawl N, operating chain Q, handle R provided with a supporting collar U; supporting bracket T provided with recess S for the reception of said handle, said pawl N being adapted to simultaneously engage said collar U, and hold said handle and said ratchet wheel and to be disengaged from said collar and handle by the action of

said ratchet wheel, substantially as and for the purpose set forth.

7. In a water supply system for fire pumps or engines the combination with the water reservoir A provided with inlet duct and with water controlling valve located near the bottom of said reservoir of an over-flow pipe B' 45 provided with a valve K' located above the level of said inlet ducts, said inlet and outlet valves being adapted to be so relatively adjusted as to maintain a constant flow of water at a uniform height near the bottom of 50 said reservoir substantially as and for the purposes specified.

8. In a water supply system for fire pumps or engines the combination with the inlet water controlling valve J and the inclosing water reservoir A of the cap or shield A' located above and extending downwardly in front of and partially around the sides of the discharge duct of said valve and adapted to check the surging motion of the water as it is 55 discharged into said reservoir substantially as and for the purposes specified.

In testimony whereof we, HENRY C. CAMPBELL, executor, and ISABELLA A. CAMPBELL and MINNIE A. MILLARD, *née* CAMPBELL, ex- 65 ecutrices, and the said GEORGE G. CAMPBELL, do hereby affix our signatures in presence of two witnesses.
